UNITED STATES PATENT OFFICE.

GEORGE F. ATKINSON, OF SAN FRANCISCO, CALIFORNIA.

PINCUSHION.

SPECIFICATION forming part of Letters Patent No. 443,739, dated December 30, 1890.

Application filed November 30, 1888. Serial No. 292,217. (No model.)

To all whom it may concern:

Be it known that I, GEORGE F. ATKINSON, a citizen of the United States, residing in the city and county of San Francisco and State of California, have invented a new and useful 5 Pinecushion, of which the following is a specification.

My invention relates to improvements in pincushions, of which the following is a specification, reference being had to the accompanying drawing and the letters referring thereto.

The drawing represents a central vertical section of a pincushion embodying my improvements.

A represents the body of the pincushion-stand.

B represents the pincushion fiber or other substance for sticking pins, needles, &c.

C represents the bodkin-holders or receptacles for articles of similar form which are not sharp-pointed.

D represents the main receptacle for thimbles and other small articles, such as buttons, &c., and D' an annular tray or receptacle formed around the base of the stand for holding similar articles, sewing material, cloth, &c.

The following is the construction of my improved combined pincushion and receptacles.

I generally form the body of the pincushion-stand upon a turning-lathe, as other articles are turned of wood, and turn the same in a lathe out of selected ornamental wood. I generally form the cushion B of the bark of the *Sequoia gigantea*; but it may be formed of the bark of other trees or of other substances.

The principal features of the invention consist in supplying the receptacles D and C around the central pincushion for the purpose of holding thimbles, needles and pins, bodkins, and other similar articles, as the pincushion may be of any design or pattern to suit the taste of the user; but the receivers are concentrically arranged in connection 45 with the pincushion in the manner represented in the drawing by the letters D and C.

The necessity of a suitable receptacle for bodkins and other articles generally used in connection with needles in sewing-work is 50 very well known, and to supply this want I have constructed the pincushion-stand shown, which, in addition to producing a highly ornamental effect, is very handy and convenient.

The receptacles C are generally bored or drilled about the size of the article to be put away, so as to hold the article in an erect position.

Having thus described my invention, what I 60 claim, and desire to secure by Letters Patent, is—

A pincushion-stand provided with a central cushion, an annular button-holding-trough receptacle surrounding the cushion, a series 65 of bodkin-holders in the bottom of the button-receptacle, and a second annular receptacle formed in and surrounding the base of the stand.

GEORGE F. ATKINSON.
